UNITED STATES PATENT OFFICE.

CHARLES G. HILL, OF NOTTINGHAM, ENGLAND.

DESIGN FOR RUFFLING.

SPECIFICATION forming part of Design No. 21,259, dated December 22, 1891.

Application filed November 30, 1891. Serial No. 413,597. Term of patent 3½ years.

To all whom it may concern:

Be it known that I, CHARLES GREY HILL, a subject of the Queen of Great Britain, residing at Nottingham, in the county of Nottingham, England, have invented and produced a new and original Design for Ruffling, of which the following is a specification, reference being had to the accompanying drawing, forming part thereof, which represents a front elevation of the ruffling embodying the features of my design.

The principal features of the design consists in two spirally-arranged chain-like figures A and B, looped in reverse directions, one over the other, at the edge of a body figure C, simu-

lating a strip of fabric, the arrangement of the chain-like figures being such that the intervening spaces appear as closely-grouped irregular panels.

As a supplemental feature of the design one chain-like figure is given a heavy or solid appearance and the other a feathery or chenille-like effect.

I claim—

A design for ruffling, substantially as herein shown and described.

C. G. HILL.
